BENCH VISE

Zeek Sutton, Piedmont, Calif.

Application August 18, 1939, Serial No. 290,837

1 Claim. (Cl. 144—307)

My invention relates to improvements in vises. The object of my invention is to provide a readily demountable bench vise of simple design and light weight construction; to provide a bench vise which may be secured to the flat top of the bench without requiring any protruding brackets to be attached to or made a part of the bench; to provide a bench vise which secures itself to the bench more tightly the greater the pressure put on the vise; to provide a bench vise having means for securing it against movement in the opposite direction; and to provide a bench vise of extreme simplicity and having only three parts.

One form of the invention is shown in the sheet of drawings attached hereto, but it is understood that my invention is capable of being embodied in other forms without departing from the spirit of the invention or the scope of the claim appended hereto.

In the drawing:

Fig. 1 is a plan view;

Fig. 2 is a side elevational view;

Fig. 3 is an end elevational view looking to the right at Fig. 1;

Fig. 4 is a view in perspective looking at the bottom or bench engaging face of the vise;

Fig. 5 is a view in perspective of a bench showing the device in position thereon and supporting a piece of wood; and

Fig. 6 is a side elevational view in cross section showing the attaching means in operative relation to the bench top.

One of the important features of my invention is the fact that it provides a readily demountable light weight planing vise which requires only one metal stamping and two sliding blocks, preferably of wood. These comprise the outer member 10 and the blocks 11 and 12.

The outer member 10 is preferably made from a metal stamping of relatively thin gauge stock so as not to lift the end of the board 30 supported in the vise too high above the bench. In this connection, if it should be found that the thickness of the metal member 10 raises one end of the board 30 too high, a strip of equal thickness can be placed under the board 30 as at 31.

The stamping 10 is formed with one lip or tongue 15 which projects downwardly, at an angle. It is preferably inclined at an angle between 30° and 45° to bottom 16. This effects a secure anchoring of member 10 to bench top 32 (see Fig. 6), where tongue 15 is shown projected into hole 25, thereby securely anchoring member 10 not only against forward or sidewise longitudinal movement, but against any tendency to be

lifted vertically. The latter tendency would be found when the vise was holding a short but high piece of wood being planed. I prefer that tongue 15 be located near the wide end of bottom 16 so as to effect a secure holding to resist any vertical lift on member 10.

Recess 17 is formed near the opposite end in member 10. It is preferable to locate it in alignment with tongue 15 and along the center line of bottom 16. Recess 17 is perforated at 18, through which perforation a nail 13 or other similar fastening means may extend. The function performed by recess 17 and nail 13 will appear in Fig. 6 where nail 13 is shown fitted into hole 26 in bench top 32. It is not necessary that nail 13 be a drive fit in hole 26 as its purpose is merely to prevent member 10 from moving to the right, that is, backwardly so as to release tongue 15 from hole 25. In practice I have found that nail 13 performs its function satisfactorily when loose enough to be lifted out by the head when grasped by the fingers.

Member 10 is also formed with side walls 19 and 20 which preferably are inclined inwardly so as to form less than a right angle with bottom 16. They may be formed at a right angle to bottom 16 but better results are obtained where they incline inwardly. In order to effect the wedging or clamping action for my vise, sides 19 and 20 are formed on bottom 16 so that at one end they are closer together than at the other end. The narrow end is the end toward which tongue 15 points, as this is the direction of force or pressure applied to the vise during use.

The blocks 11 and 12 are preferably of wood, although they may be made of metal, and have their sides 22 cut at an angle corresponding to that formed by sides 19 and 20 with bottom 16. Their inner edges 23 are at right angles to bottom 16 unless some particular use is being made of the vise which requires board 30 to be supported at less than a right angle to bench top 32. In the latter event the angle of sides 23 to bottom 16 can be made to suit.

The length of member 10 as well as the length of blocks 11 and 12, the height of sides 19 and 20 and blocks 11 and 12 will be determined by the particular use for which the vise is designed. I have found in work around the home shop that if member 10 is between six and eight inches long and the blocks are of a corresponding length, and about one inch in height, a very satisfactory result is obtained.

In installing the device on a bench, it is necessary only to drill two holes, 25 and 26. Hole 25

is drilled into the bench top at an angle corresponding to tongue 15 and hole 26 is drilled at right angles to the bench top. A clearance hole 24 is made in the bench top to receive recess 17 in bottom 16. In Fig. 6, hole 25 is not shown extending all the way through the bench, although it is preferable that it should so extend in order to be self-cleaning. It will be obvious from the description thus far that the device is not only simple and of few parts, but also may be readily detached or applied to a work bench. When lifted from the bench there are no attaching parts or brackets left on the bench top to interfere with the latter's use for other purposes. The device is small and light weight and may be carried in the carpenter's tool kit and quickly set up on a saw horse or other work supporting surface simply by drilling the two holes 25 and 26.

The economy with which this device may be manufactured lends it to ready marketability and wide spread adoption by carpenters as well as for the home work shop.

What I claim is:

A quick detachable anchoring bench vise adapted to receive objects which project beyond both ends thereof comprising a one-piece quadrilateral sheet material base having a substantially flat central portion with a depending sloping anchoring lug at one end and a perforation near the other end, one pair of opposite sides of said base lying substantially in the plane of said base, and the other pair of integral opposite sides being bent upwardly and inwardly to an angle of less than 90° to said base, said sides being straight and spaced closer together at the end toward which said anchoring lug points than at the other end, and a pair of triangular wedge members each having one edge fitted substantially to the bent up inwardly sloping sides of the one piece integral base and when so fitted, having their facing edges substantially parallel with each other.
